GEAR-WHEEL.

1,390,414.

Specification of Letters Patent. Patented Sept. 13, 1921.

Application filed July 8, 1919. Serial No. 309,303.

To all whom it may concern:

Be it known that I, ERIK HJALMAR WINGQVIST, a subject of the King of Sweden, residing at Utbynäs Villastad, Göttenborg, in the Kingdom of Sweden, have invented a new and useful Improvement in Gear-Wheels, of which the following is a specification.

The present invention relates to gear-wheels, cylindrical as well as conical, and has for its principal purpose to provide a shape of gear tooth which is considerably more capable of resistance to bending stresses than the shapes of teeth heretofore used.

In cylindrical gear-wheels as heretofore used the height of the tooth is constant along the whole breadth of the tooth, whereas in conical gear-wheels the height of the tooth is generally greatest at the base end and decreases toward the top end of the wheel. In the first instance the bending moment is constant along the whole breadth of the tooth, whereas in the second instance the bending moment is greatest at the base end of the wheel. If the tooth is broken, due for instance to an overload, the breakage will obviously occur at the point where the bending moment is greatest, and the moment of resistance is smallest, that is to say at one end of the tooth in cylindrical gear-wheels, and at the smaller end of the tooth in conical gear-wheels.

The present invention has for its purpose to decrease the risk of the teeth breaking and it consists principally in that the top surfaces of the teeth are convex in the longitudinal direction of the tooth, the bending moment thus becoming decreased at the points which are liable to break. The convex surface should preferably be so located that the height of the tooth is greatest at a point intermediate the ends of the tooth.

The invention is illustrated in the accompanying drawing. Figure 1 shows a portion of a cylindrical gear-wheel having the well known shape of the teeth. Fig. 2 shows a portion of a cylindrical gear-wheel with the teeth shaped according to the present invention. Figs. 3 and 4 show two modified shapes of teeth according to the invention.

In the figures, the dotted line α extending

through the length of the teeth is the pitch line, which in the case of a cylindrical gear 55 is a longitudinal section of the pitch cylinder.

According to Fig. 1 the height of the tooth 1 is constant along the entire breadth of the tooth, and a break, if any, will occur 60 on the dotted and dashed line 2. The dotted line 3 indicates the top surface of a tooth engaging the tooth 1.

As mentioned above, the risk of a tooth breaking is decreased in the same proportion 65 as the bending moment is decreased at the points which are exposed to breaking, which result is attained, according to the invention, by making the top surfaces of the teeth convex in the longitudinal direction of the 70 tooth, as stated above.

Such embodiment of the invention is illustrated in Fig. 2, in which the top surface 4 of the tooth 1 is convex in the longitudinal direction of the tooth. The curve of the top 75 surface 4 is symmetrical with the pitch line α , so that the middle of the tooth is the highest.

The embodiment illustrated in Fig. 3 differs from the embodiment according to Fig. 80 2 principally by the bottom surface 5 of the space between teeth being concave in the longitudinal direction, by which means the bending moment at the ends of the tooth is still more decreased, provided that the 85 height of the tooth is unchanged at the center of the tooth. By making the bottom surface of the space between teeth concave in the longitudinal direction the essential advantage is also attained that the space between teeth may be formed according to the rolling off principle by means of two cutters having plane cutting surfaces and placed at an angle to one another, which cutters, by being suitably adjusted relatively to one another and to the wheel blank, may be used for producing gear-wheels of any diameter 90 and any pitch, which result can not be attained, as is well known, by means of the ordinary profile cutters. The advantage is 95 also attained that in two meshing wheels the top surface 3 and the bottom surface 5 are caused to come nearer to one another than for instance in the construction according to Fig. 2. In view of the fact that by shaping the space between teeth by means of

100
105

two cutters arranged in the manner above described, the bottom surface 5 of the space between teeth becomes elliptically shaped in the longitudinal direction, it is suitable also 5 to make the top surface 4 of such shape.

The embodiment according to Fig. 4 differs from the embodiment according to Fig. 3 only by the height at the ends of the tooth being practically *nil*, or at any rate very 10 small as compared with the height at the center of the tooth 1.

As stated above, the invention is not limited to cylindrical gear-wheels, but it is also directly applicable to conical gear-wheels. 15 It will also be understood that the invention is applicable whether the gear-wheel has helical or straight teeth.

Finally, it is to be observed that the top surface of the tooth may be ridge-shaped or 20 angle-shaped in the longitudinal direction instead of convex, the point being located at or near the center of the tooth.

I claim:

1. A toothed gear-wheel having teeth the 25 top surfaces of which are convex in the longitudinal direction of the tooth in such manner that the height of the tooth, and thus the bending moment, is decreased toward the ends of the tooth, said teeth being shaped 30 in such manner that when meshing with the teeth of another gear wheel, they touch the latter teeth along the whole length of the tooth.

2. A toothed gear-wheel having teeth the 35 top surfaces of which are shaped elliptically convex in the longitudinal direction of the tooth in such manner that the height of the tooth, and thus the bending moment, is decreased toward the ends of the tooth, said 40 teeth being shaped in such manner that, when meshing with the teeth of another gear wheel, they touch the latter teeth along the whole length of the tooth.

3. A gear wheel according to claim 1, in 45 which the bottom surfaces of the spaces be-

tween the teeth are concave in the longitudinal direction of the teeth.

4. A gear wheel according to claim 2, in which the bottom surfaces of the spaces between the teeth are elliptically concave in 50 the longitudinal direction of the teeth.

5. A toothed gear-wheel having teeth the top surfaces of which are convex in the longitudinal direction of the tooth and having their greatest height at a point intermediate 55 the ends of the tooth, said teeth being shaped in such manner that, when meshing with the teeth of another gear wheel, they touch the latter teeth along the whole length of the tooth.

6. A toothed gear-wheel having teeth the top surfaces of which are convex in the longitudinal direction of the tooth and having their greatest height approximately at the center of the tooth, said teeth being shaped 65 in such manner that, when meshing with the teeth of another gear wheel, they touch the latter teeth along the whole length of the tooth.

7. A toothed gear-wheel having teeth the 70 top surfaces of which are ridge-shaped in the longitudinal direction of the tooth in such manner that the height of the tooth, and, thus, the bending moment is decreased 75 toward the ends of the tooth, said teeth being shaped in such manner that, when meshing with the teeth of another gear wheel, they touch the latter teeth along the whole length of the tooth.

8. A toothed gear-wheel having teeth the 80 top surfaces of which are varied in the longitudinal direction of the tooth in such manner that the height of the tooth, and, thus, the bending moment is decreased toward the ends of the tooth, said teeth being shaped in 85 such manner that, when meshing with the teeth of another gear wheel, they touch the latter teeth along the whole length of the tooth.

ERIK HJALMAR WINGQVIST.
